US00D759622S

(12) **United States Design Patent**
Dahlberg

(10) **Patent No.:** **US D759,622 S**
(45) **Date of Patent:** **** Jun. 21, 2016**

(54) **COMMUNICATIONS EQUIPMENT**

(71) Applicant: **Sony Mobile Communications AB**,
Lund (SE)

(72) Inventor: **Staffan Dahlberg**, Oxie (SE)

(73) Assignee: **Sony Mobile Communications AB**,
Lund (SE)

(**) Term: **14 Years**

(21) Appl. No.: **29/508,838**

(22) Filed: **Nov. 12, 2014**

(30) **Foreign Application Priority Data**

Jul. 30, 2014 (EM) 002511378

(51) **LOC (10) Cl.** **14-03**

(52) **U.S. Cl.**

USPC ..... **D14/138 R**; D14/344; D10/32

(58) **Field of Classification Search**

USPC ..... D14/140, 137, 138 R, 138 AB, 139, 155,
D14/191, 192, 203.1, 203.3, 203.4, 203.5,
D14/203.7, 248, 226, 218, 144, 240, 344,
D14/440, 341, 346, 448, 450, 496;
D10/30-39, 70, 65, 78, 104.1, 104.2,
D10/125; D11/3-5, 12, 19, 25; D13/168;
D8/354, 366, 402, 499; D3/215;
D15/199; 381/364, 151; 379/433.1;
455/575.1, 556.1, 556.2, 558, 575.3,
455/575.4, 575.6, 90.3; 368/10, 13, 69,
368/223; D21/329; D24/167

CPC H04B 1/03; H04B 1/385; G04G 17/083

(57) **CLAIM**

The ornamental design for communications equipment, as shown and described.

DESCRIPTION

FIG. 1 is a perspective view of communications equipment showing my new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines showing the holes in the straps depict portions of the communications equipment that form no part of the claimed design.

1 Claim, 7 Drawing Sheets
